US0D1036473S

(12) **United States Design Patent** (10) Patent No.: US D1,036,473 S
Cimatti et al. (45) Date of Patent: ** Jul. 23, 2024

**(54) DISPLAY SCREEN OR PORTION THEREOF
WITH GRAPHICAL USER INTERFACE**

(71) Applicant: **PepsiCo, Inc.**, Purchase, NY (US)

(72) Inventors: **Marco Cimatti**, Sleepy Hollow, NY (US); **Jodi T. D'Amato**, Hawthorne, NY (US); **Rachel Katz**, Irvington, NY (US); **Kate Keparutis**, New York, NY (US); **Anton Ljunggren**, New York, NY (US); **Jasmine Richards**, White Plains, NY (US); **Koby Hebborn Trout**, Brooklyn, NY (US); **Amy Wong**, Brooklyn, NY (US); **Jean Edward Page**, Austin, TX (US); **Adrian Taylor**, Austin, TX (US); **Cory Tobin**, Austin, TX (US); **Michelle Brandon**, Burlington, VT (US); **Andrew Dernavich**, Burlington, VT (US); **Elisabeth Gerber**, Burlington, VT (US); **Mark Lukasiewicz**, Burlington, VT (US); **Ben Bloodworth**, Charlottesville, VA (US); **Ashley Carwile**, Charlottesville, VA (US); **Brittany Christian**, Charlottesville, VA (US); **Tien Ho**, Charlottesville, VA (US); **David Murray**, Charlottesville, VA (US)

(73) Assignee: **PepsiCo, Inc.**, Purchase, NY (US)

(**) Term: **15 Years**

(21) Appl. No.: 29/916,998

(22) Filed: **Nov. 16, 2023**

Related U.S. Application Data

(63) Continuation of application No. 29/861,928, filed on Dec. 5, 2022, now Pat. No. Des. 1,009,928, which is

CLAIM

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet

Related U.S. Application Data

a continuation of application No. 29/844,090, filed on Jun. 27, 2022, now Pat. No. Des. 971,960, which is a continuation of application No. 29/805,308, filed on Aug. 26, 2021, now Pat. No. Des. 956,078, which is a continuation of application No. 29/688,323, filed on Apr. 19, 2019, now Pat. No. Des. 929,440.
